ABSTRACT: A portable balloting device particularly suited for use by an electorate as a manually actuated, selectively operable voting machine, characterized by a plurality of "paired" voting plungers, vote eradicating plungers, and a manually actuated balloting lever for use in preparing a final machine ballot comprising a selected slate of candidates and issue positions and then casting votes by advancing preprinted vote registering tapes in accordance with the finalized machine ballot.

BALLOTTING DEVICE

BACKGROUND OF THE INVENTION

The instant invention relates generally to voting devices and more particularly to manually operated automatic voting machines employed by electors in voting at assigned polling places and for providing a current total of the votes cast for designated candidates and issues, as well as for providing a count of the electors voting at the assigned polling places.

Heretofore, in conducting an election of candidates and issues it has been necessary for members of the electorate to mark preprinted ballots manually with means such as punching, stamping or inking devices. The votes thus cast usually have then been tallied in a manual vote counting procedure. Such operations normally require large numbers of man hours, both in the initial marking of the ballots and in the subsequent vote counting or tally operation. Furthermore, often there are valid claims of voting irregularities and recording of inaccurate results which are made possible through inadequacies inherent in this mode of conducting an election. Such inadequacies often lead to recounting the votes in a time consuming and expensive and generally unsatisfactory process.

To overcome these difficulties, electronic or electrical devices have been proposed. However, in known electronic and electrical circuits, or mechanism employing such circuits, malfunction and power losses have caused innumerable difficulties. As can be readily appreciated, inaccuracies, malfunctions, and loss of voting machine time are highly undesirable. In attempts to overcome these inadequacies, manually actuated mechanical devices have been proposed, however, these devices also have failed to meet present requirements for providing a reliable system for casting votes, as their designs do not adhere to a scheme of preferred simplicity and economy.

Furthermore, previously known devices frequently do not register or provide information normally desired in the voting process, such as, for example, a running or current count of each vote cast for opposite sides of issues and candidates, as well as a combined total of the ballots cast at a given polling place on election day.

In many instances where previously known devices and machines have been employed, costs have been found to be prohibitive. As voting machines normally are employed for only a relatively small number of man hours per year, it can be appreciated that the expenses involved in providing automatic voting machines must be maintained at a minimum level. Heretofore, the desired economy has not proven practical because of the complexity of the known voting machines.

SUMMARY OF THE INVENTION

This invention overcomes or minimizes the aforementioned difficulties through the provision of a simplified, positively actuated mechanical device which serves to provide an accurate count for the votes cast for each issue and for each candidate as well as for the total number of ballots cast during a given period.

Accordingly, an object of the instant invention is to provide a simplified voting machine for casting ballots in the exercise of the voting franchise.

Another object is to provide a manually actuated vote registering device for use in polling places.

Another object of the instant invention is to provide a manually actuated device for use in the exercise of the voting franchise which serves to provide a current count of the votes cast for each issue and each candidate and which additionally provides an accurate count of the number of electors casting ballots.

Another object is to provide a simplified, accurate and inexpensive mechanically actuated device which is capable of providing a continuous count of the votes cast for each candidate and each issue in the polling place.

Another object is to provide a portable device which is simple and economical to fabricate, which can be transported to the polling places and employed in voting booths by individual electors of the electorate manually manipulating all of the voting and tally devices.

These, together with other objects and advantages will become more readily apparent by reference to the following description and claims in light of the accompanying drawings.

10 DESCRIPTION OF THE DRAWINGS

FIG. 1 is a perspective view of an assembled voting machine embodying the principles of the present invention.

FIG. 2 is a top plan view of the machine of FIG. 1 with a portion of the housing broken away illustrating the arrangement of machine components.

FIG. 3 is a side elevation, principally in section, taken generally on line 3-3 of FIG. 2 showing the various components employed by the described embodiment of the present invention.

FIG. 4 is a sectioned elevation taken generally along lines 4-4 of FIG. 3.

FIG. 5 is a front elevation, with a portion of the housing having been removed, taken generally along lines 5-5 of FIG. 3, illustrating the counting mechanisms and preprinted tapes employed by the present invention.

FIG. 6 is a sectioned plan view taken along lines 6-6 of FIG. 3.

FIG. 7 is a sectional view taken along lines 7-7 of FIG. 3 illustrating the lockout mechanisms employed in the embodiment of the present invention.

FIGS. 8, 9 and 10 constitute illustrations of the various positions assumed by the same components during various operations of the drive means employed to advance the tapes employed by the hereinafter described embodiment of the invention.

FIG. 11 is a front view, in section, of the device provided for supplying a current total count of the number of electors or voters employing the machine, and taken generally along lines 11-11 of FIG. 3.

FIG. 12 is a perspective view of one of the plurality of tape advancing modules of the present invention.

45 DESCRIPTION OF THE INVENTION

Turning first to FIG. 1, a voting machine embodying the principles of the instant invention is illustrated generally at 10. The machine includes a housing 12 provided with a pair of access doors 14 and 16 mounted by hinges 15 and 17, respectively, to provide authorized access to the driving mechanisms of the machine or device 10. A lock 18 of conventional design and construction is provided and mounted to couple the doors 14 and 16 in a secured relationship. Mounting lugs 20 are fixed in any suitable manner to the housing 12 so that the device 10 may be bolted or otherwise fixed to supporting structure normally found within appropriate enclosures as is normally provided at polling places.

The technique employed for fabricating the housing 12 is of no particular consequence so long as the housing is made "tamper-proof". As shown, rivets 22 are employed to couple or join the various structural panels of the housing 12 together. However, it is readily apparent that other means, such as tack or spot welds, could be employed to secure the housing panels in their assembled condition.

Extending across the uppermost portion of the housing 12 is a row of aligned voting plungers 30 which extend through suitable openings provided in the housing 12. Manipulation of a plunger 30 serves to designate a candidate or an issue position for which a vote is to be cast. Mounted adjacent to the row of plungers 30 there is a "key" comprising a schedule 32 which serves to designate the candidate or issue position associated with each of the voting plungers 30. It will be appreciated that as a practical matter, at subsequent elections each of the voting plungers will be employed to cast votes for

new or different candidates and issues. Therefore, in order to facilitate reuse, the key 32 may comprise a printed card listing the candidate and issue positions on the housing. If desired, the schedule 32 is formed as a permanent plate such as a metallic sheet embossed with the names of the candidates and an identification of current issues. Such a plate is secured to the door 14 in any suitable manner, such as, for example, round head screws 33 secured by nuts disposed at the inner or lower side of the door 14.

Paired with each of the voting plungers 30 is a vote eradicating plunger 40. The purpose of the eradicating plunger 40 will hereafter be more fully discussed, however, it suffices to understand that the eradicating plunger 40 permits an elector or voter to change his vote in making a final selection of candidates and/or positions on issues. This is achieved by depressing a plunger 40 to release the paired plunger 30 without recording a vote, in order that another of the plungers 30 may be depressed thus to prepare a finalized ballot to be cast by the machine. As each of the plungers 30 is depressed, the machine is "set" to vote in a given way, however, when a lever 40, which is paired with a lever 30, is depressed, the paired lever 30 is released without registering a vote. Consequently, and as can be readily appreciated, a voter may make many preliminary selections or thus construct preliminary ballots in the process of preparing or constructing a final selection or final ballot which is established only when there has been a final depression of selected plungers 30.

After having prepared a final ballot, the elector merely manipulates a balloting lever 42 in order to cast his vote or ballot. The lever 42 drives a vote counter mechanism, hereinafter more fully described, to register the votes in accordance with the final ballot prepared through the final depression of the levers 30. As will hereinafter be more fully described, the machine also includes a ballot counter 44 which serves to provide a current count of the number of voters employing the machine in a given period of time. The counter 44 thus provides a simple means for checking or verifying the count of the individual ballots cast by each machine.

It is to be understood that as many plungers 30 and 40 may be provided as is required. These plungers may be aligned as a single bank of parallel rows, as illustrated, or if desired, the rows may be aligned as multiple pairs or banks of plungers. Should the plungers 30 and 40 be aligned in multiple banks, the housing 12 will incase the mechanism with the doors 14 being so arranged as to provide access to the mechanism through the top portion of the housing 12.

Turning now to FIG. 2, and particularly FIG. 3, there is illustrated the mechanism employed in the described embodiment of the invention. Coupled with the voting plungers 30 is a plurality of vote registering mechanisms 50. As more clearly shown in FIG. 5, each of the voter registering mechanisms 50 is of the same construction and functions in essentially the same manner to achieve a like result. Therefore, and in the interest of brevity, a detailed description of only one of the mechanisms 50 will be provided with it being understood that the remaining mechanisms 50 function in a like manner and are capable of being interchanged thus to achieve flexibility.

Looking particularly to FIGS. 3 and 12, it is noted that the mechanism 50 includes a preprinted tape 52 fed from a supply spool 54. The tape 52 ultimately is wound about a takeup spool 56. As the tape 52 is wound about the spool 56 it is caused to traverse a bearing support 58, which as a matter of convenience functions as a vote registering station.

As shown, the tape 52 is provided with indicia comprising a numerical sequence. As will hereinafter be more clearly understood, the tape 52 is advanced at support 58 in incremental steps so that each advance in the sequence indicates an additional vote for the designated candidate or issue. The spools 54 and 56 are supported by a support plate 59, as shown in FIG. 12, and are removably mounted for rotation on shafts 60 and 62, respectively. While various devices are available to prevent an overrunning of the spool 54, it has been found preferable to employ a braking device including a drum 64 fix-

edly coupled to the spool 54, a brake support block 65 fixed to the support plate 59, and a spring-biased brake shoe 66 extending from the support block 65 frictionally to engage the drum 64 for thus impeding rotation of the spool 54. The shoe 66 could be adjustably mounted, however as a practical matter, it has proven to be satisfactory to adjust the biasing means so that the shoe 66 engages drum 64 with a given or fixed pressure so that the pressure applied thereto is constant as the spool 56 draws the tape 52 from the spool 54.

With particular reference to FIG. 12, it will be appreciated that the support plates 59 impart a modular characteristic to the assembled mechanism 50. Thus, each tape 52 is mounted in a separate modular component and may be readily removed in its wound condition with a substitute therefor being supplied without encountering difficulties of the type which normally plague those handling spools of tape. In order for the plates 59 to be readily mounted within and removed from the housing 12, each plate 59 is slotted at its opposite ends thus to provide a pair of mounting slots 67 extending parallel to the longitudinal axis of the plate. Each of the slots receives one of a pair of mutually displaced transverse mounting beams 68 therein, FIGS. 3 and 6, which serve removably to support the spools in their operative disposition.

The beams 68 may be mounted in the machine in any suitable manner. It has, in practice, been found adequate to provide right-angled tabs 69, FIG. 2, removably seated in suitable slots for supporting the uppermost beam while the lowermost beam is fixed by a weld in its transverse alignment. Hence, the plates 59 are removably supported in a manner such that the tapes 52 may be advanced through an actuation of drive means coupled therewith.

In order to drive the takeup spools 56 in rotation about the shafts 62, there are provided ratchet wheels 70 fixedly secured to the spools 56. Therefore, as the ratchet wheels 70 are rotatably advanced in a given direction, the spools 56 are driven in a direction to wind or draw the tapes 52 from the spools 54. In order to function as ratchet wheels, each wheel 70 is provided with a multiplicity of ratchet wheel teeth 72. As is common in ratchet drives, the teeth of the ratchet wheels 72 are each provided with conventional camming surfaces 74 and radial stops or shoulders 76 which intersect to establish ratchet wheel detents 78. The camming surfaces 74 and stop shoulders 76 serve as means for controlling the rotation and actuation of the ratchet wheels 70.

As shown in FIG. 3, in order to prevent a counterrotation or unwinding rotation of the spools 56, a plurality of ratchet stops 80 are spring-biased to ride on the camming surfaces 74 and seat in detents 78, whereby rotation in a clockwise direction, as viewed in FIG. 3, is accommodated, while a counterclockwise rotation is precluded by the stop 80 as it is seated in one of the detents 78. Each stop 80 is biased by a supporting leaf spring 82 depending from transversely aligned and removably mounted beam 83. The springs 82 permit the stops 80 to ride outwardly as the cam surfaces 74 are advanced in engagement therewith and then force the stops 80 to seat in an associated detent 78 of the ratchet wheel 70.

As hereinbefore mentioned, the tapes 52 are drawn in steps from the spools 54 in response to the stepped rotation imparted to the ratchet wheels 70. This incremental stepping of the tapes, in effect, serves to register votes for issues and candidates since the indicia provided on the tape 52 is spaced at a distance which corresponds to one incremental step of the tape. For convenience, it has been decided that the vote registering position, designated 84, will be at the point the tape 52 crosses support 58. In other words, the number which appears on the tape as it is in position at point 84 will indicate the cumulative number of votes which have been cast for a given candidate or issue position.

In order to rotate the ratchet wheels 70 for advancing the tapes 52, the mechanism 50 further includes a reciprocally mounted drive pawl 90. Each pawl 90 is spring-biased to seat in a detent 78 and engages the adjacent shoulder 76 of a tooth 72. The pawls 90 serve to apply a lifting force to the teeth of

the wheels 70 as plungers 30 are driven upwardly thus to impart rotation to the wheels 70.

In order to drive the pawl 90, a leaf spring 92 is employed to couple the pawl 90 with the shaft of the adjacent plunger 30. Each spring 92 is fastened to a plunger 30 in any suitable fashion, such as, for example, by a conventional threaded screw 94. Hence, it will be appreciated that as the plunger 30 is depressed, the spring-biased pawl 90 rides on the camming surface 74 of an adjacent ratchet wheel 70 as the wheel is held stationary by the stop 80. When the plunger 30 moves upwardly, as viewed in FIG. 3, the pawl 90 drives against the surface of the shoulder 76 to lift the tooth and impart rotation to the ratchet wheel 70. The stop 80 is permitted to ride on the camming surface 74 as a tooth 72 is rotated in engagement therewith through the action of spring 82. This rotation imparts an incremental stepping of the wheel 70 whereby the spool 56 is forced in rotation about the shaft 62 for drawing or advancing the tape 52 one step. The associated brake shoes 66 prevent overrunning of spools 54 as the driving force is removed from ratchet wheels 70. Preferably, an additional stop or dog 96 is coupled to the plunger 30 by the screw 94 and serves as an escapement mechanism whereby backlash of the ratchet wheel 70 is further prevented.

As will be appreciated in order that a ballot be cast by the voting mechanism, it is preferable that a plurality of the plungers 30 be sequentially depressed and then released in unison so that all of the tapes 52 which are to be advanced, can be advanced one step in unison. Hence, it is highly desirable that there be provided means which permit the plungers to be depressed or forced downwardly into a depressed condition and then held there until such time as it is desired to release all of the plungers 30 and thus record the votes. Hence, each of the plungers 30 is spring-biased in a vertical direction by a tension spring 100 secured between the housing 12 and a coupling bar 102 which is mounted to extend at right angles from each of the shafts 30, as shown in FIG. 3. It is to be understood that a force manually applied to the plungers 30, in a downward direction, will cause the spring 100 to be extended in tension, when the force is removed from the plunger 30, the spring 100 will act to draw the shaft of the plunger 30 upwardly. The force applied by the spring 100 must of course be sufficient to impart rotation to the ratchet wheel 70.

In order to construct a ballot, the elector or voter selects appropriate plungers 30, as designated by the key 32, and forces them downwardly into a locked or a "set" position. This "set" position is achieved through the cooperative action of a dog 104 and a stop pawl 106. The dog 104 comprises a right-angle shoulder 105 formed on the vertical surface of the shaft plunger 30 and further includes an inclined cam surface 108 over which the pawl 106 is permitted to ride. The pawl 106 is spring-biased by a resilient supporting member or leaf spring 110 which urges the pawl 106 toward the cam surface and shoulder of the dog 104. The spring 110 is coupled to the housing 12 through a support beam 112 and a mounting bracket 114 affixed thereto. The manner in which the pawl 106 is forced into engagement with the shoulder 104 and removed therefrom is better illustrated in FIGS. 8, 9 and 10.

Since it is intended that a voter construct a "marked" ballot by depressing the plungers 30, it is desirable that means be provided for releasing the plungers 30 without imparting rotation to the wheel 70, so that the voter may change his mind prior to constructing or establishing a final ballot by depressing a finally selected group of plungers 30.

A releasing of the plungers 30 is achieved through actuation of the vote eradicating plungers 40. In other words, each plunger 30 is paired with an eradicating plunger 40 mounted adjacent thereto. The purpose of the eradicating plunger 40 is, simply stated, to withdraw the dog or pawl 90 from the shoulder 76 of the ratchet wheel 70, to permit the plunger 30 to be moved upwardly by the tension spring 100 without advancing the ratchet wheel, and then to release the plunger 30 by withdrawing pawl 106 from the shoulder 105.

Each drive pawl 90 has attached thereto a rectangular pawl extracting bail or bracket 120. This bracket serves to displace the pawl 90 in opposition to the bias of the leaf spring 92. Withdrawal of the pawl 90 is achieved at right angles to the direction of travel of the plunger 30 and a radial direction with respect to the shoulder 76 of the associated ratchet wheel.

In order to achieve the withdrawal, thus to render the drive pawl 90 inactive, each of the brackets 120 is provided at an outermost portion with a cam follower 122, FIG. 9. The follower 122 engages and cooperates with an inclined camming surface 124, FIG. 8, extending along the shaft of the adjacent eradicating plunger 40. Each surface 124 is arranged in a manner such that it passes between the driving pawl 90 and the cam 122 as the plunger 40 is displaced. It is to be understood that lateral displacement of the bracket 120 is required to be sufficient for withdrawing the pawl 90 from the detent 78 of the ratchet wheel 70. Guides 128 mounted at each side of the plunger 30, as better seen in FIGS. 4 and 8, serve to support the bracket 120 for reciprocation imparted by the spring 110 and the cam surface 124.

It will be understood that as the plunger 30 is depressed, bracket 120 will move downwardly with the plunger 30 in a manner such that the drive pawl 90 is forced by the camming surface 74 in a lateral direction. Subsequently, the pawl 90 will seat in detent 78 under the influence of the leaf spring 92, once the plunger 30 has assumed its depressed or "set" position, wherein the locking pawl 106 engages the shoulder of the dog 104 for retaining the plunger 30 in its "set" or depressed position. Should it be desired to change a vote and select another candidate or issue, it is only necessary to depress the plunger 40 so that the cam surface 124 is caused to act against cam follower 122 laterally to withdraw the drive pawl 90 from the detent 78. Hence, it will be understood that the thus initiated upward displacement of the plunger 30 will be ineffective for advancing the ratchet wheel 70 in rotation about the shaft 62.

Each of the plungers 40 is held in its "ready" or upwardly extended position by means of a tension spring 130 and bracket 132 fastened between the housing 12 and the shaft of the plunger, whereby the depression of the plunger serves to apply tension to the spring 130 so that as the depressing force is released the spring 130 will contract to draw the plunger back to its "ready" or upwardly extended position.

In order for pawls 106 to be withdrawn from the dogs 104 cams 140 are formed as arcuate extensions of the leaf springs 110 and extend into the path of the surfaces of cams 126 fixed to the plunger 40 adjacent cam surfaces 124. Withdrawal of the pawls 106 is achieved as the surfaces of the cams 126 engage the arcuate surface of cam 140 and act against the bias of the springs 110.

Consequently, when a plunger 30 is in a seated position with the pawl 106 seated against the dog 104, and the associated pawl 90 is seated in a detent 78, depression of a "paired" plunger 40 will cause a cam 124 to engage cam follower 122 and force the bracket 120 to withdraw the drive pawl 90 from the detent 78. Continued downward displacement of the plunger 40 causes cam 124 to act against cam 140 laterally to withdraw the pawl 106 from the shoulder 104, whereupon the plunger 30 is permitted to return upwardly to a "ready" position under the influence of the attached spring 100. As the downwardly applied pressure is removed from the plunger 40, it is permitted to be retracted under the influence of the spring 130. Since the drive pawl 90 is withheld from seating in the detent 78, by the action of the cam surface 124, the plunger 30 is thus permitted to be reset imparting rotation to a ratchet wheel 70, and consequently, no vote will be registered.

In view of the foregoing description of the plungers 30, it will be appreciated that it is not desirable that all of the plungers be afforded the opportunity to be displaced downwardly or depressed to a "set" position by the same voter. In other words, it is necessary that the plungers 30 be permitted to coact normally in opposed voting pairs. For example, if there are two candidates for one office, it is necessary that a voter or

elector be prevented from casting a vote for both candidates for that office. Hence, lock-out means in the form of cam blocks 142 have been provided adjacent to the lowermost end portions or protrusions 143 of the plungers 30. Each of the protrusions 143 includes a downwardly directed portion having a wedge-shaped configuration and is provided with cam surfaces 144 which serve to engage surfaces 146 of the cam blocks 142 for reasons which will hereinafter be more fully explained.

As better shown in FIG. 7, each of the cam blocks 142 is supported for displacement into and out of the path of the protrusions 143 by means of resilient pins 150. The resiliency is intended to accommodate lateral displacement of the blocks 142. The blocks 142 are vertically supported for withdrawal by a horizontal supporting bracket 152, FIG. 3, and a transversely aligned stop 153. Stop 153 includes a depending lip 154 which intersects the path of and prevents excessive withdrawal or an inadvertent removal of the blocks 142 as they are extracted from beneath the protrusions of the shaft 30. The stop 153 is connected to the housing 12 by threaded nut and screw means 155.

The blocks 142 are so arranged as to permit depression of one voting plunger 30 when all of the blocks 142 are positioned beneath the protrusions 143 of the shaft 30, FIG. 4. When a single block 142 is withdrawn from beneath the protrusions, an additional voting plunger 30 may be depressed. In other words, when all of the blocks are in position, one plunger 30 may be depressed to its "set" position, if one block 142 is withdrawn, two plungers may be depressed, if two blocks 142 are withdrawn then three plungers 30 may be depressed, and so on.

As shown, the embodiment of the present invention includes only five plungers, however, as aforementioned, it is to be understood that as many plungers 30 as are found practical and desirable may be provided in single or multiple banks. In order for an elector to select a ballot of candidates and issues, it is desirable that the plungers 30 be grouped in voting combinations, normally pairs, as aforesaid. That is, side-by-side or paired plungers 30 should be designated to represent opposing candidates and opposing issues. For example, if the first in-line plunger is employed to represent a Republican candidate, then the second in-line should be employed to designate a Democrat candidate. To achieve a condition wherein an elector can only vote for one candidate, of the pair of opposing candidates, it is desirable that a block 142 be provided for the two plungers in order to pair the plungers in opposed voting pairs. The same arrangement is to be duplicated for the third and fourth plungers, and so on down the line of voting plungers. Furthermore, the phrase "pairs of opposing candidates" is employed only as a matter of convenience and it should be readily apparent that it is intended that the device be employed where there are several opposing issues or candidates within a single political party or at a single election.

As viewed in FIG. 4, the extreme left hand plunger 30 is designated W/I which, for purposes of explanation only, identifies that plunger as being a plunger for write-in candidates, as will hereinafter be more fully discussed. The next pair of plungers 30 are designated Y and N, which, again for purposes of explanation, designate these plungers as Yes and No vote plungers for voting on issues such as, for example, a bond issue, while the right hand pair of plungers 30 are designated D and R which are herein designated to serve to identify these plungers as the plungers which when depressed and released by the balloting lever will cast a vote for a Democratic or Republican candidate competing for one office.

For purposes of explanation of the operation of the lockout blocks 142 only, it is assumed that should the left hand block 142 be withdrawn from beneath the protrusions, along with the third from the left lockout block, the right hand plunger R is free to be depressed, but the surface 144 of the protrusion 143 will force the block 144 beneath the plunger D and block depression of that plunger. As shown, the Y plunger has been

depressed, hence the N plunger cannot be depressed because of the positioning of the adjacent block 142. The write-in or W/I plunger is free to be depressed for purposes of registering a write-in vote. Should a voter decide to vote for the Democrat candidate, the block 142 will be cammed to a position beneath the R or Republican plunger thus serving to block downward movement of that plunger. The same is true of the Y and N combination.

Therefore, it can be seen that by a selective withdrawal and 10 positioning of the lockout blocks 142 a plurality of voting pairs of plungers are provided for establishing preliminary ballots to be machine cast. The preliminary ballot can selectively be changed thus to establish final ballots. In making these 15 changes, a voter will always be precluded from voting for both opposing candidates or opposing issues of voting pairs of candidates and issues as a consequence of the positioning of blocks 142.

Each of the flexible pins 150 is provided with a right-angle 20 protrusion or integral member 156. This member cooperates with a transversely disposed pivoted locking beam 158 to retain the lockout blocks 142 in their selected or prearranged positions, i.e. either beneath or out of the path of the protrusions 143. As shown in FIG. 3, when the beam 158 is pivoted about a pivot 160, provided in any suitable manner, to a block-locking position, the right-angle protrusions 156 engage either side of the beam 158. This engagement serves to retain the lockout blocks in their preselected position with respect to the plungers 30. As a practical matter, access to the lockout 25 pins 142 must be provided for. Therefore, a door 162, pivoted at 164, is provided and includes a lock 166, similar to the lock 18, which serves to secure the housing thereof against unauthorized access to the machine.

Once a voter has manipulated or depressed plungers 30 and, 30 if needed, plungers 40 for thus choosing candidate and issue positions for thus establishing a preliminary ballot, then canceling or eradicating the choice, if desired, as many times as is required for thus establishing or constructing a final ballot, it is preferable that means be provided for simultaneously driving all of the tapes 52 in unison to effect casting of the finalized ballot. The aforementioned lever 42 serves as means for initiating simultaneous activation of the tape drive means and is connected to a release beam 170 disposed adjacent and just above each of the cam members 140. The purpose of the release beam 170 is to engage each of the cams 140 and force a simultaneous withdrawal of all seated pawls 106 which have been seated in the dogs 104 as a consequence of the seating of the plungers 30. In order to achieve this, the release beam 170 is coupled to the lever 42 by means of a push-pull rod 172 having an eye 174 which receives therein a pivoted lever 176. The lever 176 is pivoted to the housing 12 by suitable pivot means 178 and functions as an actuator for displacing the beam 170.

55 The end of the lever 176, opposite pivot 178, engages a depressor cam segment 180 fixed to the lever 42 so that 90° of pivotal displacement of the lever 42 will impart 90° of pivotal displacement to the depressor cam segment 180 and thereby drive the adjacent end portion of the lever 176 in a downward direction. The beam 170 and consequently the attached lever 176 is constantly urged upwardly by a tension spring 182 fixed 60 between the housing 12 and the rod 172 by a suitable bracket means 184.

Hence, when the lever 42 is pivotally displaced through 90° 65 for forcing the cam 180 through 90° of pivotal rotation to drive the lever 176 in a downward direction, the beam 170 is thus forced downwardly into engagement with the cams 140, FIG. 9, to withdraw the pawl 106 from the shoulder of the dog 104. Tracks 186, FIG. 4, are provided for receiving the ends of the release beam 170 therein to assure a proper positioning of the beam. Hence, it will be understood that the beam 170 is aligned with the tracks 186 for vertical displacement, which displacement is imparted by the lever 42 acting through cam 180 in conjunction with the pivoted actuator 176 and push-pull rod 172 to release all of the depressed levers 30 to 70 75

effect a simultaneous withdrawal of all pawls 106 from all dogs 104. Hence, a simultaneous stepping rotation is imparted to all selected ratchet wheels 70 by a vertical advancement of all seated pawls 90 thus incrementally to advance all of the selected associated tapes one step through a stepped rotation of the appropriate takeup spools 56 for effecting a registration of votes.

As it is important to keep a current record of the number of electors or voters which have utilized or employed the machine on a given voting day, it is desirable that recording means be provided for recording each casting of a ballot by a voter at the polling place. In the described embodiment of the present invention, there has been provided a voter or ballot counter 44. The purpose of this counter is to register once for each instance the balloting lever 42 is displaced through 90°, or a final ballot is cast.

The device 44 is better illustrated in FIG. 11, and employs a prelettered or numbered tape 190 suspended between a supply roll 192 and a takeup roll 194. Rotation of the takeup spool 194 is achieved through a drive shaft 196 coupled with the lever 42. As shown in FIG. 3, the shaft 196 is supported in bearings 198 and is retained in a given position by torsion spring 200 acting to impose a torque in a predetermined direction to the shaft 196.

The device 44 is mounted in a suitable closed housing 201 and includes a pawl and ratchet escape mechanism having a spring-biased pawl 202 and a conventional ratchet wheel 204 connected to the spool 194. The pawl 202 is forced into engagement with the ratchet wheel 204 by a leaf spring 206. The spring 206 serves to support the pawl 202 in its operative position adjacent to the detents of the ratchet wheel 204. As an additional means for insuring the proper rotation of the takeup spool 194, the escape mechanism includes a spring-biased stop or pawl 208. The pawl 208 is also biased into engagement with the detents of the ratchet wheel 204 thus to prevent backlash. Control of overrun rotation of the spool 192 is achieved through a frictional coupling imposed along the bearing surface of a supporting shaft 210 which supports the supply spool for rotation. The takeup spool 194 is supported for rotation on a shaft 212 which is rotatably supported for rotation by the shaft 196. The ratchet wheel 204 is fixedly coupled to the spool 194 in a manner such that rotation of the spool is directly controlled through the escape mechanism including pawls 202 and 208 and the drive shaft 196.

In practice, it will be found highly desirable to provide for casting the aforementioned write-in votes, that is candidates and issues which are to be voted upon but which do not appear on the designating legend or "key" 32.

The present invention contemplates such operation. This is achieved by providing right-angle protrusions 220 at the uppermost ends of the plungers 30. Normally, while not shown, it is preferred that each of the plungers 30 be equipped with a protrusion 220 which may be employed as a means for registering a write-in vote for each given or specified group of candidates or issues. The lowermost portion of each protrusion 220, as viewed in FIG. 3, is provided with a marker 222, which may be embossed in the form of an X, or other indicia and will make an imprint upon a paper ballot moved or positioned beneath the protrusion when it is depressed. Hence, the device of the present invention permits a write-in and separate recording thereof along with a finally prepared machine cast ballot. While the specific candidate or issue which has been voted upon, by write-in, will not be recorded by the voting mechanism, the total number of write-in ballots will be recorded in the device as the tape of the associated mechanism 50 is caused to be advanced.

OPERATION

It is believed that in view of the foregoing description of the invention, the operation thereof is readily apparent. However, in order to assure a complete and full understanding of the disclosed embodiment of the invention, a brief resume of the operation is provided.

At the outset it may be assumed that a legend 32 designating the candidates and/or issues to be voted upon has been prepared and mounted on the housing 12. It is also assumed that the blocks 142 have been so arranged and positioned that the levers 30 are paired in opposing voting pairs, whereby only one candidate of a pair of candidates or one side of an issue can be voted by depressing levers 30. Tapes 52 will have been prepositioned so that at the first incremental step of the vote registering mechanism the numeral 1 will appear at station 58. Also, the tape 190 is so positioned that the takeup spool 194 will be advanced one incremental step at the first pivotal actuation of the lever 42. It is, of course, to be understood that the housing 12 has been secured against unauthorized entry to locks 18 and 166, and the housing 12 has been secured within a booth at a given polling place.

The voter considers the candidates and depresses a given or a selected lever 30 forcing it to its seated position wherein the pawl 90 is thus caused to be seated in the detent of the cam wheel or ratchet wheel 70 in response to actuation of a spring 72. As a plunger 30 is downwardly displaced, the cam surface 144 of the protrusion 143 forces the block 142 laterally into a position beneath the paired or adjacent plunger 30. This serves to prevent the second plunger of the pair from being depressed. If there is no block beneath a given plunger 30, the adjacent or paired plunger 30 will be blocked by displacement of the given plunger as there can then be no lateral displacement of the associated block 142 thus to permit it to be depressed. Of course, if the grouping of candidates includes three or more opposing candidates, an appropriate number of blocks will be employed to prevent a voter from registering a vote for more than one candidate, including a possible write-in candidate.

If the voter subsequently decides that he would like to vote the issue in an opposite manner, or select the other of a pair of opposed candidates, it is only necessary for him to depress the plunger 40 in order to withdraw the pawl 90 from the detent 78 and then the cam 106 from the dog 104. The depressed plunger 30 is thus permitted to be forced upwardly without imparting rotation to the ratchet wheel 70. After a voter has manipulated the levers 30 in order first to establish or construct a preliminary machine ballot, and subsequently a final or finalized ballot determining the manner in which he wishes to cast his votes, it is only necessary for him pivotally to rotate the lever 42. Rotation of the lever serves to pivot the lever 176 in a downward direction through the actuation of the depressing cam 180, whereupon the eye 174 of the push-pull rod 172 is forced downwardly. As the lever 176 is depressed the push-pull rod 172 causes the beam 170 to be displaced in a downward direction against the bias of the spring 182. As the beam 170 is caused to be depressed, it serves to engage the cam 140 acting against springs 110 thus to cause the pawls 106 to be withdrawn from the lugs or dogs 104.

At this time, it will be noted that each of the driving pawls 90 of the selectively depressed plungers is seated in a detent 78 of an adjacent ratchet wheel 70. Consequently, as the plunger 30 is biased upwardly by the spring member 100, the pawl 90 is forced against the shoulder 76 of the detent thus to impart rotation to the ratchet wheel 70. This rotation is accommodated by pawl 80 and leaf spring 82 which permits the pawl 80 to ride on the cam surface 74 as the wheel is rotated and yet lock the wheel 70 against backlash. The escapement mechanism 96 also aids in preventing backlash as the pawl 90 is withdrawn from the detent 78. This incremental motion of the ratchet wheel 70 is imparted to the takeup reel 58 for thus drawing the associated tape 52 one incremental step over the support 58 to register a vote.

As all of the votes to be cast have been determined through a final manipulation of the voting plungers 30, it will be appreciated that a single rotation or displacement of the lever 42 will serve to release all of the depressed levers 30 in a single motion, whereby all selected tapes 52 are caused to be advanced one incremental step to effect a registering or balloting of a single ballot.

A rotation of the lever 42 may be considered a casting of a final ballot which was selected and constructed by a selective operation of the plungers 30 and 40. This casting of the final ballot is also a clearing operation which serves to advance the tape 190 in the voter or ballot counter 34. This advancement of the tape 190 is accommodated by the escapement mechanism which includes spring-biased pawls 202 and 208 acting in conjunction with the drive shaft 196 coupled to the lever 42. Therefore, it will be understood that upon a single rotation of the lever 42, a counting of that ballot or that voter is effected simultaneously with the casting of the elector's ballot to register the votes in accordance with the determination and selections made by the elector.

Once the polls close, it is only necessary to open the housing 12 and extract the modular mechanism 50 including spools 54 and 56 as well as the vote register station 84 supported within the housing 12. Of course, the mechanisms 50 may be replaced during a voting day, if conditions so require.

Although the invention has been herein shown and described in what is conceived to be the most practical and preferred embodiment, it is recognized that departures may be made therefrom within the scope of the invention which is not to be limited to the details disclosed herein but is to be accorded the full scope of the claims so as to embrace any and all equivalent devices and apparatus.

I claim:

1. A balloting device for registering votes comprising:
  - A. a sealed housing including a wall having means defining therein a plurality of aligned openings;
  - B. a plurality of manually depressible plungers supported for independent axial reciprocation within said openings, each of said plungers being adapted to be manually depressed for casting a vote and preparatory to registering the vote;
  - C. plunger biasing means coupled with said plungers adapted to continuously urge the plungers into an extended disposition relative to said wall;
  - D. locking means operatively associated with each of said plungers adapted independently to secure each of said plungers in a retracted disposition, relative to said wall, in response to a manual depression thereof;
  - E. manually operable release means operatively associated with said locking means and adapted to be manually manipulated for achieving a simultaneous release of retracted plungers, whereby said plungers are displaced by said biasing means;
  - F. a plurality of prenumbered tapes, each bearing thereon a sequence of step-identifying indicia serially spaced in an equidistant relationship along the surface thereof;
  - G. tape support means associated with each of said depressible plungers supporting the tapes for incremental progression through selected portions of said device;
  - H. tape advancing means coupled with said tape support means and associated with the plurality of plungers adapted to be actuated in response to a manipulation of the release means, for simultaneously advancing the tapes through one step of incremental progression, for simultaneously registering a plurality of cast votes; and
  - I. selectively operable vote eradicating means operatively associated with the tape advancing means and with each of said depressible plungers adapted selectively to be manipulated for rendering the tape advancing means associated with selected depressible plungers inoperative, whereby registration of votes cast by a depression of the selected depressible plungers is precluded as registration of a plurality of cast votes is achieved in response to a manipulation of the release means.

2. The balloting device of claim 1 wherein said tape support means includes a plurality of tape supply spools each supporting thereon one tape of the plurality of prenumbered tapes, and a plurality of tape takeup spools each receiving thereon one tape as the tape is advanced by said tape advancing means, and said tape advancing means includes a plurality of

pawl and ratchet mechanisms, each including a ratchet wheel coupled with a takeup spool and having a plurality of peripheral detents and a displaceable pawl adapted to drive the takeup spool as the ratchet wheel operatively is rotated.

3. The device of claim 2 wherein each pawl is fixed to one of said depressible plungers through a biasing means continuously urging the pawl into engagement with a ratchet detent, and operatively is displaced concurrently with the plunger for advancing the ratchet wheel.

4. The device of claim 3 wherein the locking means includes a shoulder formed on each of said depressible plungers and releasable stop means adapted to operatively engage the shoulder as the depressible plunger is depressed and to restrain the plunger against displacement, whereby the depressed plunger is retained in its depressed disposition.

5. The device of claim 4 further comprising a vote eradicating means including a plurality of displaceable spring-biased eradicating plungers, each being mounted for reciprocation through said wall and includes a downwardly directed camming surface adapted to displace a displaceable pawl from a peripheral detent and to displace the stop means from an engagement with a shoulder, whereby as the eradicating plungers are displaced in a given direction depressed plungers are released from said locking means while said tape advancing means concurrently is rendered inoperative.

6. The device of claim 4 wherein said vote eradicating means includes a plurality of manually reciprocal eradicating plungers, each being paired with a manually depressible plunger and including means for removing a pawl from a ratchet detent and means for subsequently releasing a stop from a shoulder of the paired depressible plungers, whereby the ratchet wheel is rendered inoperative as the eradicating plunger is reciprocated.

7. The balloting device of claim 1 wherein said selectively operable vote eradicating means includes means adapted to be manually manipulated to achieve a release of said depressed plungers and simultaneously to achieve an uncoupling of said tape advancing means from the tape support means associated with said selected depressible plungers, whereby a release of the plungers is accommodated while an advance of the tapes supported by the tape support means associated with said selected depressible plungers is precluded.

8. The device of claim 7 wherein said locking means includes a plurality of dogs, each comprising a shoulder formed on one of said plungers and a spring-biased locking pawl continuously urged into a seating disposition relative to the shoulder, and said manually operable release means includes an elongated bar operatively associated with the locking pawl and adapted to be manually displaced for simultaneously displacing the pawls from a seated relationship with the shoulders of the plurality of dogs, whereby a simultaneous release of said plurality of plungers is achieved.

9. The device of claim 8 further comprising a balloting lever coupled with said elongated bar in a manner such that the bar is displaced as a manipulation of the balloting lever is effected.

10. A balloting device comprising:

- A. a lockable housing;
- B. operable balloting means mounted within said housing including a plurality of modules, each module being employed for registering single votes and including an independently removable support plate seated in said housing, said plate mounting a support spool having wound thereabout a preprinted tape bearing indicia indicative of the number of increments through which the tape is incrementally advanced through said device, an advanceable takeup spool coupled with one end of said tape adapted to receive thereon the tape in a wound disposition as the tape incrementally is advanced, and tape advancing means including a pawl and ratchet mechanism interconnected with said takeup spool adapted to impart incremental rotation to the takeup spool for incrementally advancing the tape to achieve a registering of a vote;

- C. a plurality of manually operable spring-biased voting plungers connected with the balloting means, each plunger being operatively associated with a pawl and ratchet mechanism and adapted to be depressed for casting a single vote to be registered through an advancement of the tape and to be elevated for activating a pawl and ratchet mechanism, whereby an incremental advancement of said tape is effected;
  - D. a manually displaceable balloting lever operatively coupled with said balloting means adapted to be manually displaced for actuating the balloting means to elevate the depressed plunger; and
  - E. selectively operable vote eradicating means operatively associated with the voting plungers and balloting means adapted to be selectively operated prior to the displacement of the balloting lever for preventing an activation of pawl and ratchet mechanisms associated with selected voting plungers as the plungers are elevated, whereby an incremental advancement of selected preprinted tapes is precluded.
11. The device of claim 10 further comprising lockout

means operatively associated with said voting plungers, as the plungers are arranged in side-by-side alignment and operatively coupled in opposed voting pairs, adapted to respond to a depression of a voting plunger to render adjacent voting plungers inoperative.

5 12. The combination of claim 11 further characterized in that each voting plunger includes a wedge-shaped camming protrusion and said lockout means comprises: a plurality of spring-biased, laterally displaceable blocks, each block having 10 a curved cam surface disposed in the path of at least one of the wedge-shaped protrusions of the plungers of each voting pair and so arranged as to be engaged by and laterally displaced from the path of the protrusion of one plunger of a pair of adjacent plungers and pinned by the protrusion in blocking 15 alignment with the protrusion of the other plunger of the voting pair to render the other plunger inactive, and means for selectively rendering the lockout means inoperable.

13. The device of claim 11 further comprising means defining a registered vote counter adapted to be actuated by said 20 balloting lever to provide a total of all votes registered.
